(57) **CLAIM**

The ornamental design for a steering wheel, as shown and described.

DESCRIPTION

FIG. 1 is a front view of a steering wheel showing our new design;

FIG. 2 is a rear view thereof;

FIG. 3 is a top view thereof;

FIG. 4 is a bottom view thereof;

FIG. 5 is a left side view thereof;

FIG. 6 is a right side view thereof;

FIG. 7 is a right side front perspective view thereof; and,

FIG. 8 is a left side front perspective view.

Surface ornamentation, logos, written matter which forms no part of the claimed invention is disclaimed. It will be understood that the broken lines shown in the drawings illustrate portions of the steering wheel that form no part of claimed design.
